UNITED STATES PATENT OFFICE

2,489,868

DOUBLE POCKET GARMENT OF THE PATCH
POCKET TYPE

Lelia Dowling and John R. Dowling, Denver, Colo.

Application May 10, 1947, Serial No. 747,228

2 Claims. (Cl. 2—253)

1

This invention relates to improvements in garment pockets and has particular reference to pockets for outer garments such as shirts and jackets.

During the warm seasons of the year, many workmen wear no coats nor blouses, but work in what is popularly called the "shirt sleeves." As an example of workmen for which this invention is more especially intended, attention is called to filling station operators; such workmen frequently collect money and are in need of a safe and convenient pocket in which to carry the same until it can be deposited in the cash register.

The principal object of this invention is to produce a pocket that shall be readily accessible.

Another object is to produce a pocket into and from which articles may be conveniently inserted and removed and which shall offer a maximum resistance to accidental removal.

The above and other objects that will appear as this description proceeds are obtained by means of a construction and an arrangement of parts that will now be described in detail and reference for this purpose will now be had to the accompanying drawing in which the invention has been illustrated, and in which:

Figure 1 is a front elevational view of a man showing a shirt provided with the improved pocket;

Figure 2 is a fragmentary plan view of a portion of a garment showing the double pocket in place thereon, portions being broken away to better disclose the construction;

Figure 3 is a section taken on line 3—3, Figure 2;

Figure 4 is a section taken on line 4—4, Figure 2;

Figure 5 is a fragmentary plan view similar to that shown in Figure 2, in which the greater portion of the outer pocket material has been removed to show the inner or side opening pocket; and

Figure 6 is a section taken on line 6—6, Figure 2.

Referring now to the drawing, reference numeral 10 designates a shirt and reference numeral 11 designates the patch pocket secured thereto and to which this invention relates. In the remaining figures reference numeral 12 designates the garment material and reference numeral 13 the material of the patch pocket which material may be the same kind as that used for the garment. In the drawing the pocket material 13 has been shown as provided with two pleats 14

2

forming a boxpleat 15, which may or may not be used in the actual construction. The pocket material 13 is secured to the garment material along a vertical side and the bottom edge by means of stitching 16. The stitching also extends upwardly along the other vertical side to a point designated by numeral 17. The upper corner of the pocket material is connected with the garment material at 18 by means of suitable stitching.

- 10 It will be observed that so far as the description has proceeded, the pocket is merely an ordinary patch pocket open at the top and open for substantially half the height of the pocket along the edge designated by reference numeral 19. 15 The opening formed by the unstitched portion 19 is the throat or entrance to the safety pocket which has been designated by reference numeral 20. The safety pocket has the appearance of an elbow, the convex edge 21 thereof being at the 20 top and the concave edge 22 at the bottom. In Figure 5 the concave edge has been shown as comprising two angularly related sections forming an angle at the point designated by 22. However, this can be varied so as to provide a more gradual 25 curve than that shown. It is also permissible to make the entrance to the pocket somewhat narrower, in which case the lower edge of the safety pocket can be upwardly slanting along the line designated by reference numeral 23. 30 Referring now to Figure 2, it will be observed that the two side walls of the safety pocket have their edges along the entrance opening secured to the garment member 12 and to the edge of the pocket material 13 by means of stitching. The 35 inner wall member of the safety pocket is secured to the garment material 12 by stitching 24 and the corresponding edges of the outer safety pocket wall are secured to the corresponding edge of the pocket material 13 by a row of stitching 25. A 40 folded strip 26 of cloth of a different color is interposed between the inner surface of the pocket material 13 and the corresponding edge of the outer wall of the safety pocket. The purpose of strip 26 is to give the parts a finished appearance 45 and since this may be made from cloth of a different color, it adds an ornamental and pleasing effect and also serves to give the garment a distinctive appearance that can be employed in the nature of a trade-mark to indicate origin. 50 The pocket material 13 is unattached to the garment material 12 along the upper horizontal edge and access can therefore be had to the patch pocket through the opening at the top. Access to the safety pocket can only be had 55 through the opening 19 which extends down-

wardly from the upper edge of the pocket material.

Referring now to Figure 1, it will be evident that due to the fact that the safety pocket opens along a vertical edge, it will be readily accessible without necessitating the awkward position of the arm and hand that is required to permit the fingers to enter the pocket from above.

Referring now again more particularly to Figure 5, attention is called to the peculiar construction of the safety pocket which terminates in that portion which has been designated by reference numeral 27, which is bounded by the upwardly extending edge 28 providing a sack-like recess that serves to keep any objects therein in place.

When the pocket is worn by filling station operators, for example, the safety pocket is very convenient for the purpose of keeping paper and silver money temporarily until it can be deposited in the cash register. The downwardly extending portion of the safety pocket that has been referred to above and designated by reference numeral 27, although it is easily accessible by inserting a finger of the right hand thereinto in the manner indicated by Figure 1, also makes it practically impossible for the contents of this pocket to accidentally fall out during normal working positions.

This safety feature is further enhanced by the fact that the safety pocket is not attached to the garment cloth or to the outer pocket material 13, thereby permitting it to move freely with respect to the materials between which it is positioned.

From the above description and from the drawing it will be apparent that the double pocket that has been shown and described results in an added convenience to the wearer of a garment thus constructed. The handkerchief, for example, may be inserted in the patch pocket from above and any other articles such as cash or cigaret packages or tools may be inserted in the safety pocket so that it can be readily removed when desired, but which will resist forces tending to remove such material accidentally.

Having described the invention, what is claimed as new is:

1. A safety pocket for shirts and the like, consisting of a patch pocket open at the top, one vertical side and the bottom being stitched to the garment, the other vertical side being stitched at its extreme top to the garment and open thence downwardly, for substantially one-half its length, forming a pocket opening, stitching along the vertical side aforesaid extending from said pocket opening to the bottom stitching, the patch pocket thereby forming a pocket space bounded by said stitchings and a safety pocket of substantially elbow shape having its open end stitched to the garment and the edge portion of the patch material at the pocket opening, said safety pocket being disposed within in the pocket space formed by the patch pocket, the convex portion of the safety pocket being towards the top.

2. In a double pocket construction of the patch pocket type, comprising a garment, a substantially rectangular patch positioned thereon with two edges vertical and two horizontal, one vertical edge and the lower horizontal edge being stitched to the garment along their entire length, the other vertical edge being secured for a portion of its length upwardly from the lower edge by stitching and at its top, leaving a pocket opening, a curved, elbow shaped, pocket having its open end secured to the wall of the pocket opening so that it may be entered through said opening, the convex edge of the pocket being at the top, whereby objects positioned in the pocket will be supported at the lower end thereof and prevented from falling out by the convex inner edge of the pocket.
